United States Patent Office

Des. 181,825
Patented Dec. 31, 1957

181,825

JAR

Robert P. Vuillemenot, Oradell, N. J., assignor to The Procter & Gamble Company, Cincinnati, Ohio, a corporation of Ohio

Application June 20, 1956, Serial No. 41,984

Term of patent 14 years

(Cl. D58—25)

FIG. 1.

FIG. 2.

FIG. 3.

FIG. 4.

The characteristic features of my design for the jar disclosed reside in the indented pattern appearing on the base of the jar as shown.

I claim:

The ornamental design of a jar, as shown and described.
